ALDEN H. PACKARD, OF WOBURN, MASSACHUSETTS, ASSIGNOR OF ONE-HALF TO
J. DONALD ROBBINS, OF BOSTON, MASSACHUSETTS.

GATE LIFTING AND RELEASING MECHANISM FOR ELEVATORS.

1,425,332.

Specification of Letters Patent. Patented Aug. 8, 1922.

Application filed August 22, 1921. Serial No. 494,046.

To all whom it may concern:

Be it known that I, ALDEN H. PACKARD, citizen of the United States, residing at Woburn, in the county of Middlesex and State of Massachusetts, have invented new and useful Improvements in Gate Lifting and Releasing Mechanism for Elevators, of which the following is a specification.

This invention relates to a gate operating attachment carried by a freight elevator car and including a gate engaging member adapted, when the car is ascending, to first engage and lift and then release a gate or a series of gates controlling access to the elevator well, and, in descending, to be displaced and to pass by all the closed gates in its path.

The object of the invention is to provide a simple, durable and effective mechanism adapted to be conveniently installed on a car without material modification or alteration of the car, and of such nature that a gate of ordinary construction may be readily adapted for cooperation therewith.

The invention consists in the improvements which I will now proceed to describe and claim.

Of the accompanying drawings forming a part of this specification,

Figure 1 is a side elevation showing an attachment embodying the invention and portions of a car and of a gate.

Figure 2 is a top plan view of the attachment.

Figure 3 is a view similar to Figure 1 on a reduced scale and showing a portion of the platform of the elevator the entire length of the gate and portions of a building.

Figure 4 is a perspective view of the head portion of the attachment.

Figure 5 is a perspective view of the projection attached to the gate to adapt it for cooperation with the attachment.

Figure 6 is a fragmentary view similar to portions of Figure 1 showing the head partially displaced from its normal position.

Figures 7, 8, 9, 10 and 11 are fragmentary views illustrating the operation.

The same reference characters indicate the same parts in all of the figures.

An attachment embodying my invention includes a holder adapted to be attached to a portion of an elevator such as one of the uprights 12 rising from the elevator platform 13, said holder being formed to project outward from the portion to which

it is attached and to support at its outer portion a hinge connecting a tilting head with the holder. As here shown the holder is substantially triangular and includes a vertical base 14 seated on the upright 12 and attached thereto by bolts or screws 15, said base being preferably a flat sided metal strip or bar, and an angular portion, preferably formed by bending a flat sided bar 16 of the same cross section as the base and of greater length, to form ears 17 secured by rivets 18, or otherwise, to the base 14, oppositely inclined portions 19, and a neck 20 connecting said portions and formed as a loop or socket adapted to receive a hinge pindle 21. Said pindle forms an element of a hinge connection between the holder and the tilting head 22. Other elements of said connection are two spaced apart rearwardly projecting ears 23 attached to the head and perforated to receive the pindle 21. The said hinge connection is located between opposite ends of the head and permits the head to tilt on a substantially horizontal axis. The head is provided at its opposite end portions with V-shaped strikers 24 and 25 arranged in tandem order, one being above and the other below said hinge connection. The head and its strikers are preferably formed by imparting to a metal bar of the same cross section as those forming the holder, two V-shaped bends constituting the strikers.

The head is normally maintained with the strikers in vertical alinement with each other by means preferably embodied as next described. To the head are fixed vertical plates 27 bridging the reentrant inner sides of the strikers, each plate being attached at one end by a bolt 28 and at its opposite end by a stud 29 entering a socket in the head. The plates 27 are provided with apertures 30 through which loosely pass the outer end portions of spring-supporting bolts 31. Said bolts are pivoted at 32 to the plates 27 and are extended through orifices or guides 33 in the ears 17 and base 14 of the holder. With the outer end portions of the rods 31 are engaged spring abutments, each preferably formed by a washer 35 and nuts 36, the latter engaging screw threaded portions of the rods. Between the said abutments and the ears 17 are interposed springs 38 of equal force and acting to hold the strikers in vertical alinement with each other and to permit either

striker to be displaced inward and the other outward.

40 represents a gate adapted to slide vertically in an opening above a floor 41, the 5 upper end face of said opening being shown at 42. The gate is adapted to cooperate, as hereinafter described, with the strikers, by attaching to its upper portion a projection which is preferably V-shaped and composed 10 of a wooden block 44 attached to the upper portion of the gate, and a metal shoe or reinforcing plate 45 attached to the block. The apex of the projection is in the path 15 of the strikers and the arrangement is such that the operation may be as follows:

When the elevator is ascending from a point below a closed gate 40, the upper striker 24 strikes the gate projection as indicated by Figure 1, and lifts the gate until 20 the latter is arrested by the face 42, as shown by Figure 3. If the elevator is stopped in the position shown by Figure 3, the upper striker holds the gate open until the elevator is again moved. If the elevator before stopping moves upward far enough to carry the upper striker above the gate projection, the upper spring 38 yields and the head 22 is first tilted as shown by Figure 6, and then returns to its normal position so 25 that the gate projection is between the strikers when the elevator stops, the gate being arrested by the lower striker 25, as indicated by dotted lines in Figure 7. If the ascent of the elevator is continued the lower spring 30 38 yields and the head is again tilted until the lower striker 25 rides across the apex 35 of the gate projection, the lower spring then acting to return the head to its normal position when the lower striker is above the 40 gate projection. The gate now drops to its closed position. When the elevator is descending and the lower striker 25 encounters a projection on a closed gate arrested by a 45 floor 41, this striker is displaced by the projection, as indicated by Figure 9, and passes below the projection, as shown by Figure 10. If the descent of the elevator is continued, the upper striker 24 then encounters and is displaced by the gate projection, as 50 shown by Figure 11, and finally leaves said projection, the head being then restored to its normal position. The upright 12 is provided with sockets 47 formed to permit the necessary endwise movements of the rods 31 55 caused by the tilting of the head.

When the elevator is descending the gates remain closed, the strikers slipping across the projections of the several gates. When the elevator stops in its descent at any floor, 60 the gate at that floor may be raised by hand, until its projection 44 engages the lower striker 25, as indicated by dotted lines in Figure 7. The gate is thus held in a raised position until the elevator moves either upward or downward and releases the gate.

It will now be seen that the gates are automatically raised only when the elevator is ascending.

I claim:

1. A gate lifting and releasing attachment for elevators, comprising a holder having means for rigid attachment to an elevator, a tilting head, a hinge connection between the holder and head permitting the holder to tilt on a substantially horizontal axis, the head being provided at opposite end portions with V-shaped strikers arranged in tandem order, one above and the other below said hinge connection, and means for yieldingly maintaining the head with its strikers 70 in vertical alinement with each other, the upper striker being adapted to engage a projection on a gate and lift the latter when the elevator is ascending, the upper and lower strikers being adapted to be successively 75 displaced by said projection when the elevator is ascending and the raised gate is arrested, and the lower and upper striker being successively displaceable by the projection 80 when the elevator is descending and the gate is closed.

2. A gate lifting and releasing attachment for elevators, comprising a holder having means for rigid attachment to an elevator, a tilting head, a hinge connection between 95 the holder and head permitting the holder to tilt on a substantially horizontal axis, the head being provided at opposite end portions with V-shaped strikers arranged in tandem order, one above and the other below said hinge connection, springs arranged to act on the opposite end portions of the head and yieldingly maintain the head with its strikers in vertical alinement with each 100 other and means for supporting said springs 105 in their operative relation to the head.

3. A gate lifting and releasing attachment for elevators, comprising a substantially triangular holder, including a base portion seated on and adapted to be attached 110 to an upright portion of an elevator, and an angular bar attached at its ends to said base and having a socket at its apex, a tilting head having inwardly projecting hinge members midway between its ends, a pintle 115 engaged with said hinge members and with the holder socket, said ears, pintle and socket constituting a hinge connection between the holder and the head permitting the head to tilt on a substantially horizontal axis, the 120 head being provided at its end portions with V-shaped strikers arranged in tandem order, one above and the other below said hinge connection, and means for yieldingly maintaining the head with its strikers in 125 vertical alinement with each other, said strikers being adapted to cooperate as described with a projection on a gate.

4. A gate lifting and releasing attachment for elevators, comprising a holder having 130

means for rigid attachment to an elevator, a tilting head, a hinge connection between the holder and head permitting the holder to tilt on a substantially horizontal axis, the 5 head being provided at opposite end portions with V-shaped strikers arranged in tandem order, one above and the other below said hinge connection, spring supporting rods pivotally connected with opposite end 10 portions of the head adjacent to the strikers and movable endwise in guides in the holder, spring abutments on the outer end portions of said rods, and springs supported by said rods between said abutments and portions 15 of the holder, said springs yieldingly maintaining the head with its strikers in vertical alinement with each other and permitting the described cooperation of the strikers with a projection on a gate.

20 5. A gate lifting and releasing attachment for elevators, comprising a substantially triangular holder, including a base portion seated on and adapted to be attached to an upright portion of an elevator, and an 25 angular bar attached at its ends to said base and having a socket at its apex, a tilting head composed of a bar provided midway between its ends with rearwardly projecting

ears, a hinge pintle engaged with said ears and with the holder socket to form a hinge 30 connection between the holder and head permitting the head to tilt on a substantially horizontal axis, the end portions of the head-forming bar being bent to form V-shaped strikers arranged in tandem order, one 35 above and the other below said hinge connection, apertured plates attached to the head and bridging the inner sides of the bent striker-forming portions, spring-supporting rods passing loosely through the apertures in 40 said plates and pivoted to the latter, said rods being movable endwise in guides in the holder, nuts engaged with said rods and forming adjustable spring abutments on the outer end portions of the rods, and springs 45 supported by the rods between said abutments and portions of the holder, said springs yieldingly maintaining the head with its strikers in vertical alinement with each other and permitting the described co- 50 operation of the strikers with a projection on a gate.

In testimony whereof I have affixed my signature.

ALDEN H. PACKARD.
